Primary Examiner — Marianne N Pandozzi*Assistant Examiner* — Jae Liang(57) **CLAIM**

The ornamental design for a glass, as shown and described.

DESCRIPTION

FIG. 1 is a front top perspective view of a glass showing my new design;

FIG. 2 is a front bottom perspective view thereof;
FIG. 3 is a side elevational view of the design with the other side view being the same;FIG. 4 is a top elevational view of our design; and,
FIG. 5 is a bottom plan view thereof.

The broken line portions in the drawings are for illustrative purposes and do not form part of the claimed design.
